(57) **CLAIM**

The ornamental design for the tri-fold egg carton, as shown and described.

DESCRIPTION

FIG. 1 is a top perspective view of a tri-fold egg carton.

FIG. 2 is a bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is an enlarged view thereof, taken along and in the direction of line FIG. 9-FIG. 9 of FIG. 8.

The dash-dash broken lines showing an egg carton illustrates portions of the tri-fold egg carton. The dash-dot-dot broken lines showing two eggs illustrate environmental structure. The dash-dot broken lines represent the bounds of the claim. The broken lines form no part of the claimed design.
